Maxson Automatic Machinery Company, West-
erly, R. I., a corporation of Rhode Island

Application January 14, 1949, Serial No. 70,930

43 Claims (Cl. 271—64)

1

The present invention relates to feeding-and-stacking methods and machines, and more particularly to methods of and machines for feeding and stacking sheet material, like paper or board.

A machine of the above-described character in common use comprises a plurality of tapes for feeding the sheets into a lay-boy, where they become stacked upon a main support. The main support is automatically lowered by degrees to maintain the top of the stack of sheets at substantially constant height, thereby permitting the feeding means to continue feeding the sheets into the lay-boy on top of the stack without hindrance from the sheets already there. When the main support becomes lowered to the floor, however, it becomes necessary to remove it, and to substitute therefor a new main support on which to stack further sheets. It is essential, at such times, either to shut down the machine, so as to prevent the feeding of further sheets into the lay-boy or else, as where high-speed production is required, to provide some mechanism that renders it unnecessary to interrupt the continuous feeding of the sheets.

According to the invention disclosed in my co-pending application, Serial No. 748,813, filed May 17, 1947, now Patent No. 2,521,075, September 17, 1950, the problem is solved with the aid of an auxiliary support on which temporarily to stack the sheets during the removal of the completed stack on the main support and the substitution therefor of a new main support, after which the sheets temporarily stacked on the auxiliary support must be transferred to the substituted main support. This solution of the problem has proved to be very efficient, enabling the feeding and stacking of sheets of any practical length, of any weight stock.

As an alternative solution of the problem of maintaining continuous operation of the machine during the removal of the completed stack of sheets, it has been proposed to switch the feeding of the sheets from one lay-boy to another upon the completion of the stack. A proposal of this character, however, does not lend itself easily to the feeding of overlapped sheets, because the switching mechanism can not operate to deflect continuously fed overlapped sheets from one lay-boy to another unless there is a break in the feed of the overlapped sheets during which the switching mechanism may operate.

In order to solve the switching problem in systems employing overlapped sheets, therefore, it has been proposed to feed the sheets singly to

2

start out with, and not to start the overlapping until the sheets have traveled beyond the position of location of the switch. This proposal, however, requires high-speed timing and synchronization, and changing the direction of travel of the sheets at times when they are traveling singly at high speed, prior to their becoming overlapped.

An object of the present invention, therefore, is to provide a new and improved method of and machine for switching the sheets while traveling at low speed after they have been overlapped, and during the continuous operation of the machine.

A further object is to provide a new and improved feeding-and-stacking machine adapted for the employment of a new and improved switching mechanism for switching overlapped sheets from one path of travel to another path during the continuous operation of the machine.

Still another object is to provide a new and improved switching mechanism for switching overlapped sheets in the low-speed section of the feeding-and-stacking machine.

Other and further objects will be explained hereinafter and will be particularly pointed out in the appended claims.

The invention will now be more fully described in connection with the accompanying drawings, in which Figs. 1 and 1A together constitute a diagrammatic view, in front elevation, of a paper-cutting-and-feeding machine embodying the present invention, in preferred form, the joining line being indicated as A—A; Fig. 2 is a section, upon a larger scale, taken upon the line 2—2 of Fig. 5, looking in the direction of the arrows; Fig. 3 is a plan, also upon a larger scale, of the switching mechanism illustrated in Fig. 1A, the conveyor tapes being omitted, for clearness; Fig. 4 is a front elevation, also upon a scale larger than in Figs. 1 and 1A, but smaller than in Fig. 3, of the motor-driving system illustrated in Fig. 1A for operating the switching mechanism and related parts; Fig. 5 is a corresponding plan, with parts in section and other parts omitted, for clearness; Fig. 6 is a fragmentary rear elevation of a detail, illustrating pull chains for operating the motor-driving system to control the switching mechanism; Fig. 7 is a schematic circuit diagram illustrating the electrical circuit connections of the motor-driving system in a fragmentary plan setting; Fig. 8 is a front elevation corresponding to the plan of Fig. 3; and Fig. 9 is a transverse vertical section taken upon the line 9—9 of Fig. 5, looking in the direction of the

arrows, but upon a larger scale, illustrating the details of a slidable block and a pawl-and-ratchet device for controlling the motor-driving system, the relative positions of the parts illustrated in Fig. 9, however, being different from those illustrated in Fig. 5.

The drawings illustrate a paper-sheet-cutting-and-feeding machine of well-known type, such as is commonly employed in paper mills to cut webs from a roll or rolls into sheets, and feeding the sheets by means of more or less horizontal conveyor tapes, into a lay-boy.

A web 1 is led from, for example, a roll (not shown) of paper or similar material between a feed roll 5 and a cooperating drum 4, by which the paper is advanced past disc cutters 2, which sever the paper into longitudinal strips of the desired width, over a guide board 11, to a stationary bed-knife cutter 10. The drum 4 is shown geared to a main drive shaft 3, driven from a variable-speed transmission unit 7 by a chain 6. The term "web," "paper," "sheet" or its equivalent, will be employed herein to denote either a single layer or a plurality of superposed layers of the paper, board or other material. A rotary cutter 9, operated synchronously with the feeding of the web by the feed roll 5 and the drum 4, as, for example, by means of a chain 8, also connected to the variable-speed transmission unit 7, cooperates with the bed cutter 10 to cut the traveling web 1 into sheets 80 of the desired length. The invention is equally applicable to machines for feeding previously cut sheets.

Owing to the feeding action of the roll 5 and the drum 4, aided by gravity, the sheets 80 travel, at a downward incline, over a guideboard 12, toward a series of cooperating high-speed conveyor tapes or belts 16 and 18. The tapes or belts 16 and 18 are mounted over rolls driven from a chain 15. A chain 13 drives an intermediate shaft 14 from, and therefore in synchronism with, the drum 4; and the shaft 14, in turn, drives the chain 15 to operate the tapes or belts 16 and 18. The forward end roll of the tapes 18 is shown at 24. Sloping or inclinedly disposed tapes 17, also driven by the chain 15, are positioned between the bed cutter 10 and the tapes or belts 16 and 18, in the path of feeding movement of the sheets 80, in order gradually to straighten out the head or cut end of each sheet, if it should happen to be curled, thereby facilitating proper feeding of the sheets 80. Similar apparatus is described, for example, in Letters Patent 2,261,968, issued November 11, 1941, to Louis L. Matthews.

The sheets 80 thus fed between the cooperating high-speed conveyor tapes 16 and 18 are advanced to relatively low-speed tapes 22 on which, because of the reduction in speed, the sheets 80 become overlapped. The relatively low-speed tapes 22 are mounted over rolls the forward roll of which is shown at 123. The tapes 22 are operated by a sprocket chain 53 from a shaft 51 that is driven by a pulley 99. The sprocket chain 53 is mounted over a sprocket 52, shown more particularly in Figs. 1, 4 and 5, mounted upon the shaft 51 of the pulley 99. The pulley 99, in turn, is driven by means of an endless V-belt 98 from a pulley 97, disposed upon the shaft of a motor 93. The motor 93, therefore, determines the speed with which the overlapped sheets 80 are advanced by the relatively low-speed conveyor tapes 22, as before explained.

A crimpler mechanism 20 may be employed to impart a long lengthwise stiffening wave to the

sheets, as described, for example, in Letters Patent, 2,281,704, issued May 5, 1942, and an air blower 19 may be employed to blow air under the head of each sheet 80, while it is still traveling at high speed, and just before its change of speed by the relatively low-speed tapes 22, as described, for example, in Letters Patent 2,261,971 issued November 11, 1941, both to the said Louis L. Matthews. A slow-down carriage 21 for slowing down the speed of the head of each sheet may also be employed, as described, for example, in Letters Patent 2,261,972, issued November 11, 1941, to the said Louis L. Matthews.

The relatively low-speed tapes 22 are overlapped by, and separated from, the high-speed tapes 18, as shown. The sheets 80 are thus fed at relatively high speed, confined by the tapes 16 and 18, to the relatively low-speed tapes 22, but become unconfined by the tapes 16 and 18 upon becoming advanced to the low-speed tapes 22.

The relatively low-speed tapes 22 feed the overlapped sheets 80 to a horizontally disposed guide plate 26, illustrated more particularly in Fig. 8, that is supported on an angle iron 25 just beyond the forward end roll 123 of the tapes 22. The guide plate 26 is preferably positioned very close to, and just forward of, the end roll 123 of the tapes 22 in the line of feed of the sheets 80, and its horizontally disposed upper surface is disposed just slightly lower than the top of the end roll 123, in order to maintain a smooth flow of overlapped sheets from the tapes 22.

As the sheets 80 travel forward over the horizontally disposed upper surface of the guide plate 26, they are received on a plurality of parallel switch fingers 23, spaced transversely of the machine and of the direction of travel of the sheets 80. The switch fingers 23 are adapted to occupy selectively any of a plurality of different angular positions. Three such positions are illustrated, respectively designated by the numerals 23-I, 23-II and 23-III. Since the switch fingers 23 can not occupy more than one of these three positions at a time, two of these three positions, in any particular figure, are illustrated by dashed lines. In order to enable adjusting the switch fingers 23 to the different positions 23-I, 23-II and 23-III, they are shown mounted upon an angle iron 27 that is secured to a rod 28. The rod 28 may be mounted in oppositely disposed end bearings 29, one of which is illustrated in Fig. 3. The rod 28 may be freely rocked in its bearings 29, as by means of a handwheel 30, correspondingly to rock the angle iron 27, and thereby to adjust the switch fingers 23 about the axis of the rod 28 to any of its three angular positions 23-I, 23-II and 23-III. The switch fingers 23 may, of course, be counter-balanced to permit of very free angular adjustment.

In order to hold the switch fingers 23 locked securely in any of their three positions 23-I, 23-II and 23-III of adjustment, a small pin or rod 33, shown more particularly in Figs. 3 and 8, is passed through a spoke in the handwheel 30 and into one of a plurality of holes, shown three in number at 81, 82 and 83, provided in a bracket 31 secured to the frame of the machine. The rod 33 may be removed from the hole 81, 82 or 83 in which it may happen to be disposed—say, the hole 81, corresponding to the position 23-I—by pulling outward upon a small handle 32, at its outer end, in opposition to the action of a coil spring 34 wound about the rod 33 between the handwheel 30 and a pin 35 extending diametrical-

ly through the rod 33. The handwheel 30 becomes thereupon free to be turned to bring the switch fingers 23 to each of its other positions 23-II and 23-III, whereupon, upon the release of the handle 32, the rod 33 will become actuated by the coil spring 34 into the hole 82, or the hole 83, as the case may be.

In the position 23-II, for example, as illustrated by full lines in Fig. 1A and by dashed lines in Fig. 8, the switch fingers 23 may direct the sheets 80 substantially horizontally forward to a series of approximately horizontally disposed, though shown inclined slightly upward in Fig. 1A, cooperating conveyor tapes or belts 36 and 37 for conveyance to a first lay-boy, marked "A." In this first lay-boy "A," the sheets 80 become stacked or piled upon a skid support or platform 88. The customary front stop and side and rear jogger blades for assuring even stacking or piling on the support or platform 88 are not illustrated. Constructions for effecting this result are described, for example, in the said Letters Patent 2,261,972, and Letters Patent 2,367,416, issued January 16, 1945, to the said Louis L. Matthews. As the sheets continue to be fed into the lay-boy "A," and become stacked or piled on the skid support or platform 88, the skid support or platform 88 becomes automatically lowered by degrees, in order to maintain the level of the stack or pile of sheets 80 approximately uniform. This may be effected in any desired manner, as described, for example, in Letters Patent 1,545,912, issued July 14, 1925, to Charles B. Maxson. In time, the skid support or platform 88 will become lowered to the floor, as illustrated in Fig. 1A.

According to a feature of the present invention, the switch fingers 23 are then angularly adjusted by means of the handwheel 30, so as to occupy the position 23-I. In this position 23-I, the switch fingers 23 will direct the sheets 80 forward at an upward incline, to a series of conveyor tapes or belts 38 and 39, and then between an approximately horizontal position of the tapes 38 and a series of approximately horizontally disposed conveyor tapes 40, for conveyance to a second lay-boy, marked "B." The conveyor tapes and belts 38 and 39 may assume different forms, as illustrated, for example, in Figs. 1A and 8. In this second lay-boy "B," the sheets 80 become stacked or piled similarly to their stacking or piling in the first lay-boy "A," but upon a skid support or platform 89 that has previously been adjusted so as to occupy a level just below that of the delivery of the sheets by the conveyor tapes 38 and 40 into the lay-boy "B," as illustrated in Fig. 1A. The automatic jogging systems employed in connection with the lay-boy "A" may be employed also in connection with the lay-boy "B"; and air supplies 41, shown schematically in Fig. 1A, and crimpers, of the nature already described, may be employed also in connection with both the lay-boys "A" and "B." It is to be understood, however, that side-unloading lay-boys or any other types of sheet-receiving receptacles may be employed to stack the overlapped sheets fed from the conveyor tapes 38, 39, 40 or 36, 37. The conveyor tapes 36, 37, 38, 39 and 40 are shown operated from a sprocket chain 55, shown more particularly in Figs. 1A and 4. The chain 55 is shown engaging a sprocket 54 driven by the shaft 50 of a pulley 49. The pulley 49, in turn, is driven by means of an endless V-belt 48 from a pulley 47 mounted upon the shaft of a motor 92. The motor 92 thus deter-

mines the speed with which the overlapped sheets 80 that have been fed beyond the switch fingers 23 are fed to the lay-boy "A" or to the lay-boy "B."

During this feeding of the sheets 80 into the second lay-boy "B," the stack or pile of sheets that has been completed in the lay-boy "A" is removed, and a new skid support or platform 88 is raised to its highest level in the lay-boy "A." Upon the completion of the stacking or piling of the sheets on the skid support or platform 89 in the lay-boy "B," the operator will readjust the orientation of the switch fingers 23 to the position 23-II, once more, so as to retransfer the feed of the sheets from the lay-boy "B," to the lay-boy "A." In this manner, it becomes possible to provide a continuous feeding and stacking of the sheets 80, without shutting down the machine in order to enable removing the completed stack, or pile of sheets on the skid support 88 in the lay-boy "A," or that on the skid support 89 in the lay-boy "B."

To adjust the switch fingers 23 back and forth between the positions 23-I and 23-II, however, is not an easy task, because of the continuously overlapping nature of the feed of the sheets 80 to these switch fingers 23. So long as the feed of the sheets 80 by the low-speed tapes 22 to the switch fingers 23 remains continuous and overlapping, it is not possible, during the feeding of the sheets, to move the handwheel 30, in order to alter the orientation of the switch fingers 23 from one direction to another, between the positions 23-I and 23-II, for example, without causing a jamming of the feed. The problem could, of course, be solved by shutting down the machine during the adjustment of the switch fingers 23.

In accordance with a feature of the present invention, however, it is not necessary to shut down the machine. Provision is made, instead, for rendering a predetermined region of the machine in the vicinity of the switch fingers 23 clear of the overlapped sheets 80. With the switch fingers 23 clear of the overlapped sheets 80, there is no difficulty involved in changing their orientation. So long as there are no overlapping of the sheets 80 upon the switch fingers 23, the operator may, first, remove the rod 33 from the hole 81, 82 or 83 that it may happen to occupy; then, turn the handwheel 30 to adjust the switch fingers 23 to any desired angular position; and, finally, reinsert the rod 33 into the hole 81, 82 or 83 corresponding to the newly adjusted position. The feed of the overlapped sheets 80 in the vicinity of the switch fingers 23 may thereupon be resumed, and the machine will from then on continue to feed the overlapped sheets from the relatively low-speed tapes 22 along the readjusted direction to the lay-boy "A" or the lay-boy "B," as the case may be.

It has been explained that, in the position 23-I of the switch fingers 23, as illustrated by full lines in Fig. 8, the overlapped sheets 80 will be advanced by the tapes 38, 39 and 40 for conveyance into the lay-boy "B"; and that, in the position 23-II of the switch fingers 23, the tapes 36 and 37 will similarly advance the overlapped sheets 80 into the lay-boy "A." In the third position 23-III, the switch fingers 23, under the control of the operator, will deflect the overlapped sheets 80 into a chute, between guide members 43 and 44, through a hole 42 in the floor, into a reject receptacle, not shown. It may be desirable to discard sheets 80 in this manner at times when, for example, without shutting down the machine,

5 a change is made in the length of the strips cut by the cutters 9 and 10 by suitable adjustment of the variable-speed transmission unit 7. The sheets of improper length thus produced at such times may then be prevented from reaching the lay-boy "A" or the lay-boy "B."

The preferred mechanism for clearing the switch fingers 23 of the overlapping sheets 80 will now be described. It has been explained that the motor 93 controls the speed of the relatively low-speed tapes 22 and, therefore, the speed with which the overlapped sheets 80 are advanced by the relatively low-speed tapes 22 to the switch fingers 23. It has been explained also that the motor 92 controls the speed of the tapes 36, 37, 38, 39 and 40 and, therefore, the speed with which the overlapped sheets are carried by these tapes away from the switch fingers 23. Ordinarily, under normal operating conditions, the motors 92 and 93 operate at the same speed, in order to drive the conveyor tapes 36, 37, 38, 39 and 40 at the same speed as the conveyor tapes 22 and, therefore, to carry the overlapped sheets 80 away from the switch fingers 23 as rapidly as they are advanced to the switch fingers 23 by the relatively low-speed tapes 22. Under normal operating conditions, therefore, the overlapped sheets are advanced at the same speed along the relatively low-speed tapes 22, over the switch fingers 23, and along the tapes 36 and 37 into the lay-boy "A," or by the tapes 38, 39 and 40 into the lay-boy "B."

Let it be assumed, as before, that the switch fingers 23 initially occupy their horizontally disposed position 23-II, as shown by full lines in Fig. 1A, in order that the relatively low-speed tapes 22 may advance the overlapped sheets 80 over the switch finger 23 to the tapes 36 and 37, for stacking in the lay-boy "A." Upon the skid support or platform 88 in the lay-boy "A," reaching the floor with a completed full stack of sheets 80, it becomes desirable to switch the feed of the overlapped sheets 80 from the conveyor tapes 36 and 37 to the conveyor tapes 38, 39 and 40. This, as already explained, may be effected by manipulating the switch fingers 23 from the horizontally disposed position 23-II to the upwardly inclined position 23-I, illustrated by full lines in Fig. 8. It has also been explained that, in order to effect this result without shutting down the machine, it is desirable to clear the region of the switch fingers 23 of the overlapped sheets 80.

According to the preferred embodiment of the invention that is illustrated and described herein, the speed of the sprocket chain 53 is reduced, in order that the low-speed conveyor tapes 22 may become slowed down to even a lower speed; and the speed of the sprocket chain 55 is at the same time increased, in order simultaneously to speed up the conveyor tapes 36 and 37. The region in the vicinity of the switch fingers 23 becomes thus temporarily cleared quickly of all sheets 80. This is because the speed with which further overlapped sheets 80 are advanced to the switch fingers 23 by the relatively low-speed tapes 22 becomes temporarily reduced, and, at the same time, the speed with which the tapes 36 and 37 pass into the lay-boy "A" the overlapped sheets 80 already previously advanced to the switch fingers 23 becomes temporarily increased, in order to snatch them away from the switch fingers 23. The temporary further slowing down of the speed of the low-speed tapes 23, of course, results in temporarily increasing the degree of overlap-

ping of the sheets 80 on the relatively low-speed tapes 22, but this is not a drawback.

The operator may thereupon: first, pull outward on the handle 32, thereby to disengage the pin 33 from the hole 82; than, turn the hand-wheel 30, as before explained, in order to adjust the switch fingers 23 to the position 23-I; and, finally, release the handle 32 to insert the pin 35 in the hole 81, thereby locking the switch fingers 23 in the readjusted position 23-I. This operation may be performed rather leisurely if the region of the switch fingers 23 is cleared of the sheets 80 rapidly by the tapes 36 and 37, and if the conveyor belts 22 are slowed down to a sufficiently low speed to advance the next following overlapped sheets 80 toward the switch fingers 23 very slowly. After the switch fingers 23 become locked in the position 23-I, the speed of the sprocket chain 53, and hence the speed of the conveyor tapes 22, is again increased to their former predetermined speed. The speed of the chain 55 is at the same time reduced to its former predetermined speed, thus effecting the decrease of the speed of the conveyor tapes 38, 39 and 40. The preferred mechanism for attaining this result will now be described.

To slow down the speed of the relatively low-speed tapes 22, the shaft 51, upon which is mounted the sprocket 52 for driving the sprocket chain 53 from which the relatively low-speed tapes 22 are driven, as before described, may be disconnected from the drive of the motor 93, and connected, instead, to the drive of a motor 94. To increase the speed of the tapes 36 and 37, the shaft 50, upon which is mounted the sprocket 54 for driving the sprocket chain 55 from which the tapes 36, 37, 38, 39 and 40 are driven, may be disconnected from the drive of the motor 92, and connected, instead, to the drive of a motor 91 of higher speed. The mechanism for disconnecting the shafts 51 and 50 from the drives of the respective motors 93 and 92 will be described presently.

As for the mechanism for connecting the shaft 51 to the drive of the motor 94, the shaft 51 is shown provided with a second sprocket 61 driven from a sprocket chain 60 that passes over a sprocket 59 mounted upon a shaft 58. Through the medium of a worm-gear reduction unit 56, 57, the motor 94 will drive the shaft 58, and hence the shaft 51, at reduced speed compared with the before-mentioned predetermined relatively low-speed drive of the motor 93, to drive the relatively low-speed tapes 22 at a very slow speed.

The shaft 50 is similarly shown provided with a sprocket 64 driven from a second sprocket chain 63, shown more particularly in Fig. 4, that passes over a sprocket 62 mounted upon the shaft of the motor 91. The motor 91 drives the shaft 50 at a high speed compared with the before-mentioned predetermined relatively low-speed drive of the motor 92, to drive the tapes 36, 37, 38, 39 and 40 at a correspondingly greater speed.

As an illustration of a practical operating system, the motors 93 and 92 may normally drive the respective shafts 51 and 50, and hence the relatively low-speed tapes 22 and the tapes 36, 37, 38, 39, 40, respectively, at a predetermined normal speed such as to advance 125 feet of sheets per minute. Assuming that the feed roll 5 and the drum 4 feed the web 1 at a rate corresponding to 250 feet of sheets per minute, a fifty-percent overlap of the sheets 80 will be produced. Upon the shaft 51 becoming disconnected from the motor 93, however, it may be driven from

the motor 94, through the worm-gear reduction unit 56, 57, at a speed reduced by a factor of eleven-twelfths, to a speed one-twelfth its normal predetermined speed. The relatively low-speed tapes 22 will therefore be driven at the abnormally low-speed of about 10 feet of sheets per minute. Upon the shaft 50 becoming disconnected from the motor 92, on the other hand, it may be driven by the motor 91 at a speed, increased by a greater factor of one, double its predetermined normal speed of 125 feet of sheets per minute, or 250 feet of sheets per minute. If the motors 92 and 93 are disconnected from, and the motors 91 and 94 are connected to, their respective shafts 50 and 51 at substantially the same time, therefore, the overlapped sheets 80 will be snatched away from the switch fingers 23 by the tapes 36 and 37 about twenty-five times as fast as the relatively low-speed tapes 22 will feed additional overlapped sheets 80 toward the switch fingers 23. This will result in a very rapid clearing of the switch fingers 23 of sheets 80.

A similar operation will take place, of course, when, assuming that the switch fingers 23 occupy their position 23-I, as illustrated by full lines in Fig. 8, it is desired to adjust them to the dashed-line position 23-II of Fig. 8, or the full-line position of Fig. 1A, for deflecting the sheets 80 from the lay-boy "B" to the lay-boy "A," or to the reject chute 43, 44, as before explained.

In some instances, instead of simultaneously reducing the speed of feed of the overlapped sheets 80 prior to their reaching the predetermined region of the switch fingers 23, and increasing the speed forward of the region of the switch fingers 23, it may be desirable to perform the one operation only of reducing the speed of feed of the sheets 80 by the relatively low-speed tapes prior to their reaching the switch fingers 23, and without increasing the speed of the tapes 36 and 37. This one operation, of course, will still effect the feeding of the sheets 80 by the relatively low-speed tapes 22 to the switch fingers 23 at the very low speed of about 10 feet of sheets per minute. This may be a low enough speed to effect sufficient clearance of the overlapped sheets 80 for a sufficient period of time to permit adjustment of the switch fingers 23 from one of the positions 23-I, 23-II, or 23-III to another. It may similarly be desirable, without reducing the speed of the relatively low-speed tapes 22, merely to increase the speed of operation of the tapes 36 and 37. This will also clear to some extent the region of the switch fingers 23 of sheets 80. In such cases, however, the operator will be more hurried in his manipulation of the hand wheel 30 to adjust the switch fingers 23 from one of the positions 23-I, 23-II and 23-III to another than when both the relatively low-speed tapes 22 are slowed down and the tapes 36 and 37 are increased, as before described.

It remains now to describe the preferred mechanism for disconnecting the drive of the motors 92 and 93, respectively, from the shafts 50 and 51 and, at the same time, to connect these shafts to the drives of the respective motors 91 and 94.

The motors 91, 92, 93 and 94 are shown in Figs. 1A, 4 and 5 bolted to pairs of transversely disposed cross bars 47 that are secured to a common base comprising two longitudinally disposed front and rear frame members 45 and 46. The shafts 50 and 51 are shown mounted on brackets 65.

The pulley 49, which, as previously explained, drives the shaft 50 from the motor 92, is not, however, integral with this shaft 50. On the contrary, it is loose upon the shaft 50. As illustrated more particularly in Figs. 2 and 5, the pulley 49 rotates the shaft 50 through the medium of a pawl 66. The pawl 66 is shown pivoted to an integral arm 79 of the pulley 49 upon a stud 100, shown as a headed bolt. Its free end is provided with a tapered edge 84. The tapered edge 84 is yieldingly forced by a spring 85 into engagement with a multi-toothed ratchet 67 that is fixed to the shaft 50. It is only when the spring 85 holds the tapered edge 84 of the pawl 66 in engagement with the ratchet 67 that the pulley 49 may drive the shaft 50. When the pawl 66 becomes disengaged from the ratchet 67, in opposition to the action of the spring 85, the pulley 49 is driven loosely by the motor 92, without any longer driving the shaft 50. The pawl-and-ratchet systems 166-167, 266-267 and 366-367 hereinafter described, are all identical with the system 66-67 above described. The reference numerals are the same in these various systems except that, for distinguishing purposes, they are increased by 100, 200 and 300, respectively.

The sprocket 64, driven by the sprocket chain 63 from the motor 91, is also loose upon the shaft 50. The sprocket 64 is integrally provided with an arm 179, similar to the integral arm 79 of the pulley 49, upon which is similarly pivoted at 200 a pawl 166, similar to the pawl 66 of the pulley 49, provided with a tapered edge 184 for engaging a multi-toothed ratchet 167, similar to the ratchet 67, and that, like the ratchet 67, is fixed with the shaft 50. The motor 91 will drive the shaft 50 at times only when the pawl 166 is in engagement with the ratchet 167. When the pawl 166 is in engagement with the ratchet 167, however, the motor 91 will drive the shaft 50 at a speed greater than the drive of the shaft 50 by the motor 92 when the pawl 66 engages the ratchet 67. The reasons for this difference in speed of the shaft 50 when driven by the motors 91 and 92 has already been explained. These different speeds may be attained in any well-known way.

The pulley 99 for driving the shaft 51 from the motor 93 is similarly provided integrally with a similar arm 279 upon which is pivoted at 300 a similar pawl 266 having a tapered edge 284 for engaging a similar ratchet 267 that is fixed to the shaft 51. The motor 93 will therefore drive the shaft 51 at times only when the corresponding pawl 266 engages the corresponding ratchet 267. The sprocket 61, driven from the motor 94, finally, is likewise integrally provided with an arm 379 having a similar pawl 366, more particularly shown in Fig. 9, having a tapered edge 382, for engaging a similar ratchet 367 fixed to the shaft 51. The sprocket will drive the shaft 51 at times only when this pawl 366 engages the ratchet 367. The drive of the shaft 51 by the respective motors 93 and 94 through the respective ratchet-and-pawl systems 266-267 and 366-367, however, as before explained, is at different speeds. It is for this purpose that the worm-gear reduction unit 56, 57 is employed.

In order simultaneously to disconnect the motors 92 and 93 from the respective shafts 50 and 51, and in order simultaneously to connect the respective motors 91 and 94 to the respective shafts 50 and 51, two blocks 68 and 168

are slidably mounted concentrically about the respective shafts 50 and 51, as illustrated more particularly in Figs. 5 and 9. The blocks 68 and 168 are disposed intermediately of their respective shafts 50 and 51 between the ratchets 67 and 167 and the ratchets 267 and 367, respectively. The slidable blocks 68 and 168 are tapered at their ends 101 and 102 in order to enable them to slip under the tapered edges 84, 184, 284 and 384 of the respective pawls 66, 166, 266 and 366, respectively, thereby to lift the pawls out of engagement with their respective ratchets 67, 167, 267 and 367. The blocks 68 and 168 may occupy two extreme positions of slidable adjustment on their respective shafts 50 and 51. In one extreme position of its slidable adjustment, illustrated in Fig. 5, the tapered end 102 of the block 68 engages under the tapered edge 184 of the pawl 166 in order to lift that pawl 166 out of engagement with the ratchet 167, thereby to render the motor 91 ineffective to drive the shaft 50. As the other tapered end 101 does not, in this position, engage under the tapered end 84 of the pawl 66, however, the spring 85 causes the pawl 66 to engage the ratchet 67 in order to render the motor 92 effective to drive the shaft 50. This ineffectiveness and effectiveness of the respective motors 91 and 92 is reversed, of course, in the other position of adjustment, not illustrated in Fig. 5, of the block 68. The motors 93 and 94 are similarly rendered relatively effective and ineffective in the two extreme positions of slidable adjustment of the block 168.

When the block 68 is slidably adjusted along the shaft 50, to its other extreme position of slidable adjustment, not illustrated in Fig. 5, on the other hand, it assumes the relative position illustrated by block 168 in Fig. 5. Its tapered edge 101 becomes then disposed under the tapered edge 84 of the pawl 66 to lift the pawl 66 out of engagement with the ratchet 67. In these relative positions of the parts, the motor 92 no longer drives the shaft 50. In this same position of the slidable block 68, however, the tapered end 102 of the block 68 releases the pawl 166, enabling it to engage the ratchet 167. The motor 91 will therefore drive the shaft 50.

In the relative positions illustrated by Fig. 5, similarly, the sliding block 168 occupies an extreme position of slidable movement on the shaft 51 such that the pawl 266 engages the ratchet 267 in order to render the motor 93 effective to drive the shaft 51 through the pawl 266 and the ratchet 267. The lower tapered end 102 of the block 168, however, engages under the tapered edge 384 of the pawl 366 to cause the pawl 366 to become disengaged from the ratchet 367, thereby to render the motor 94 ineffective to drive the shaft 51. In the other extreme position of slidable adjustment of the block 168, illustrated in Fig. 9, on the other hand, the tapered end 101 of the block 168 disengages the tapered edge 384 of the pawl 366, and its tapered end 101 engages the tapered edge 284 of the pawl 266. The spring 385 therefore causes the pawl 366 to engage the ratchet 367 in order to render the motor 94 effective to drive the shaft 51, and the pawl 266 is at the same time disengaged from the ratchet 267 in order to render the motor 93 ineffective to drive this shaft 51.

To slide the blocks 68 and 168 from one extreme position of slidable adjustment to the other, they are pivotally connected at 72 on opposite sides of the pivot 70 of a swinging arm

69 that is intermediately pivoted upon a cross-bar 86, secured to the longitudinally disposed frame members 45 and 46. Cords or pull chains 71 and 171 fastened to the respective ends of the arm 69, may be actuated to move that arm 69 about its intermediately disposed pivot 70 to adjust the slidable blocks 68 and 168 slidably in opposite directions simultaneously along their respective shafts 50 and 51. In one extreme position of pivotal adjustment of the arm 69, therefore, as illustrated in Fig. 5, the pawls 66 and 266 will simultaneously engage the respective ratchets 67 and 267 to enable the motors 92 and 93 to become effective to drive the respective shafts 50 and 51 simultaneously. The motor 93 will at this time, therefore, drive the tapes 22 and the motor 92 the tapes 36, 37, 38, 39 and 40 simultaneously at the same predetermined normal speed. The motors 91 and 94 will at this time be ineffective. In the other extreme position, not illustrated, of pivotal adjustment of the arm 69, the pawls 166 and 366 will engage the respective ratchets 167 and 367 to enable the motors 91 and 94 to become effective to drive the respective shafts 50 and 51 simultaneously. The motor 94 will therefore drive the relatively low-speed tapes 22 at reduced speed and the motor 91 will at the same time speed up the tapes 36, 37, 38, 39 and 40 to clear the region of the switch fingers 23 of the sheets 80, as previously described, in order to permit of adjusting the position of the switch fingers 23. The motors 92 and 93 will at this time be ineffective.

35 It is preferred, insofar as possible, in order to protect the operator, to position the drive mechanisms on one side only of the machine, which may be termed the driving side, and the control mechanisms on the opposite side, which may be termed the operator's side. The pull chains 71 and 171 may, therefore, extend transversely across the machine from the driving side of the machine toward the operator's side. The pull chains 71 and 171 are shown in Fig. 5 extending from the respective ends of the arm 69 forward toward the operator's side of the machine horizontally. They are then guided under lower pulley wheels 73 and 173, respectively, mounted on the front frame member 45; after which the pull chains 71 and 171 extend upward and diagonally rearward, shown more particularly in Figs. 1A, 4 and 6; and over upper pulley wheels 273 and 373, respectively, provided on the under side of an upper rear rail 74, adjacent the forward ends of the conveyor tapes 18 and 22. The cords 71 and 171 or pull chains are then carried forward over the respective pulleys 273 and 373 towards a front upper rail 174, and their free ends are fastened to a second swinging arm or bar 75, as shown more particularly in Figs. 3, 7, and 8, that is intermediately pivoted at 78 on a bracket 77 that may be secured inside the front upper rail 174 of the machine. In order to swing the bar 75, a handle 78, illustrated in Figs. 1A, 3, 7 and 8, may be connected to one of its ends. The handle 78 is shown extending through the upper front rail 174 to render it accessible to the operator, preferably near the handwheel 30, as illustrated in Figs. 1A, 3 and 7. The operator may thus operate the pull chains or cords 71 and 171 from his position at the handwheel 30, merely by pushing or pulling upon the handle 78. The swinging bars 69 and 75 are shown substantially parallel, and they will remain substantially par-

parallel in all positions of adjustment of the handle 78.

Electric limit switches 103 and 104 are illustrated in Fig. 7 as disposed at opposite sides of one end of the arm 75, and similar switches 105 and 106 are shown disposed at corresponding opposite sides of the other end of arm 75. In one extreme position of pivotal adjustment of the arm 75, the limit switches 104 and 105 will be closed, as illustrated. The pawl 66 will, at the same time, engage the ratchet 67, and the pawl 266 the ratchet 267, to connect the motors 92 and 93 into circuit, in order to drive the respective shafts 50 and 51. The circuit connections to the motors 92 and 93 from the respective closed switches 104 and 105 are diagrammatically illustrated in Fig. 7 at 87 and 95. The switches 104 and 105 may, for example, close the field circuits or any other suitable circuits of the respective motors 92 and 93, at this time, in order to permit the motors 92 and 93 to operate while connected to the respective shafts 50 and 51. The other switches 103 and 106 are at this time open, in order to prevent operation of the motors 91 and 94, thus saving power while they are disconnected from the shafts 50 and 51.

In the other extreme position of pivotal adjustment of the arm 75, similarly, these switches 103 and 106 will be closed to permit operation of the motors 91 and 94 at the time that they are connected to the respective shafts 50 and 51. Connections of the respective switches 103 and 106 to the respective motors 91 and 94 are respectively indicated diagrammatically at 96 and 107. The switches 104 and 105 are open, at this time, in order to prevent the motors 92 and 93 from drawing power unnecessarily.

The limit switches 103, 104, 105 and 106 may be so mounted that there shall be a momentary neutral point, in which none of these switches are closed. Notwithstanding this momentary neutral point, however, the conveyor tapes will continue to operate, because they are mounted over anti-friction rolls that enable them to coast for several revolutions, even after the power is all shut off. This passing through a neutral point, therefore, in combination with the multi-toothed ratchets 67, 167, 267 and 367, provides for a smooth and a practically silent shifting of the drive.

A description of many portions of the machine an understanding of which is not essential to an understanding of the present invention has purposely been omitted and many parts of the machine have purposely not been illustrated in order not to detract attention from the features of essential novelty. Fuller explanations of such portions of the machine will be found in the Letters Patent above referred to. It will be understood that the features of novelty may be embodied in other machines and in machines of other types and that modifications may be made by persons skilled in the art without departing from the spirit and scope of the invention as defined in the appended claims.

What is claimed is:

1. A method of feeding sheets that comprises feeding the sheets to a predetermined region at a predetermined speed, feeding the sheets thereafter beyond the predetermined region along a predetermined direction, reducing the speed of feed of a plurality of the sheets below the predetermined speed prior to their reaching the predetermined region in order to clear the predetermined region of sheets, thereupon transferring

the feed of the sheets from the predetermined region along a different predetermined direction, and thereafter increasing the reduced speed of the sheets prior to their reaching the predetermined region.

2. A method of feeding sheets that comprises feeding the sheets to a predetermined region at a first predetermined speed, feeding the sheets thereafter beyond the predetermined region at a second predetermined speed along a predetermined direction, reducing the speed of feed of a plurality of the sheets below the first predetermined speed prior to their reaching the predetermined region, increasing the speed of feed of a plurality of the sheets above the second predetermined speed beyond the predetermined region in order to clear the predetermined region of sheets, and thereupon transferring the feed of the sheets from the predetermined region along a different predetermined direction.

3. A method of feeding sheets that comprises feeding the sheets to a predetermined region at a first predetermined speed, feeding the sheets thereafter beyond the predetermined region at a second predetermined speed along a predetermined direction, reducing the speed of feed of a plurality of the sheets below the first predetermined speed prior to their reaching the predetermined region, increasing the speed of feed of a plurality of the sheets above the second predetermined speed beyond the predetermined region in order to clear the predetermined region of sheets, and thereupon transferring the feed of the sheets from the predetermined region along a different predetermined direction.

4. A method of feeding sheets that comprises feeding the sheets to a predetermined region at a first predetermined speed, feeding the sheets thereafter beyond the predetermined region at a second predetermined speed along a predetermined direction, reducing by a predetermined factor the speed of feed of a plurality of the sheets below the first predetermined speed prior to their reaching the predetermined region, increasing by a greater factor the speed of feed of a plurality of the sheets above the second predetermined speed beyond the predetermined region in order to clear the predetermined region of sheets, and thereupon transferring the feed of the sheets from the predetermined region along a different predetermined direction.

5. A method of feeding sheets that comprises feeding the sheets to a predetermined region and thereafter beyond the predetermined region along a predetermined direction at a predetermined speed, reducing the speed of feed of a plurality of the sheets below the predetermined speed prior to their reaching the predetermined region, increasing the speed of feed of a plurality of the sheets above the predetermined speed beyond the predetermined region in order to clear the predetermined region of sheets, and thereupon transferring the feed of the sheets from the predetermined region along a different predetermined direction.

70 6. A method of feeding sheets that comprises feeding the sheets to a predetermined region and thereafter beyond the predetermined region along a predetermined direction at a predetermined speed, reducing the speed of feed of a plurality of the sheets below the predetermined

upon transferring the feed of the lapped sheets from the predetermined region along a different predetermined direction.

17. A method of feeding sheets that comprises feeding the sheets in lapped relation to a predetermined region at a predetermined speed, feeding the lapped sheets thereafter beyond the predetermined region at a predetermined speed along a predetermined direction, reducing by a predetermined factor the speed of feed of a plurality of the lapped sheets prior to their reaching the predetermined region, substantially simultaneously increasing by a greater factor the speed of feed of a plurality of the lapped sheets beyond the predetermined region in order to clear the predetermined region of sheets, thereupon transferring the feed of the lapped sheets from the predetermined region along a different predetermined direction, and thereafter increasing the reduced speed of feed of the lapped sheets prior to their reaching the predetermined region and substantially simultaneously reducing the increased speed of feed of the lapped sheets beyond the predetermined region.

18. A method of feeding sheets that comprises feeding the sheets in lapped relation to a predetermined region, feeding the lapped sheets thereafter beyond the predetermined region along a predetermined direction at a predetermined speed, increasing the degree of lapping of a plurality of the lapped sheets prior to their reaching the predetermined region, substantially simultaneously increasing the speed of feed of the lapped sheets above the predetermined speed beyond the predetermined region in order to clear the predetermined region of sheets, and thereupon transferring the feed of the lapped sheets from the predetermined region along a different predetermined direction.

19. A method of feeding sheets that comprises feeding the sheets in lapped relation to a predetermined region, feeding the lapped sheets thereafter beyond the predetermined region along a predetermined direction at a predetermined speed, increasing the degree of lapping of a plurality of the lapped sheets prior to their reaching the predetermined region, substantially simultaneously increasing the speed of feed of the lapped sheets above the predetermined speed beyond the predetermined region in order to clear the predetermined region of sheets, thereupon transferring the feed of the sheets from the predetermined region along a different predetermined direction, and thereafter reducing the degree of lapping of the lapped sheets prior to their reaching the predetermined region and substantially simultaneously reducing the increased speed of feed of the lapped sheets beyond the predetermined region.

20. A method of feeding and stacking sheets that comprises feeding the sheets in lapped relation to a predetermined region, feeding the lapped sheets thereafter beyond the predetermined region along a predetermined direction, stacking the sheets fed along the predetermined direction, increasing the speed of feed of a plurality of the lapped sheets beyond the predetermined region in order to clear the predetermined region of the lapped sheets when the stack has attained a predetermined height, thereupon transferring the feed of the lapped sheets from the predetermined region along a different predetermined direction, stacking the lapped sheets fed along the different predetermined direction, and decreasing the increased speed of the lapped

sheets beyond the predetermined region upon the commencement of the stacking of the lapped sheets fed along the different predetermined direction.

21. A method of feeding and stacking sheets that comprises feeding the sheets in lapped relation to a predetermined region, feeding the lapped sheets thereafter beyond the predetermined region along a predetermined direction, stacking the sheets fed along the predetermined direction, reducing the speed of feed of a plurality of the lapped sheets prior to their reaching the predetermined region, substantially simultaneously increasing the speed of feed of a plurality of the lapped sheets beyond the predetermined region in order to clear the predetermined region of sheets when the stack has attained a predetermined height, thereupon transferring the feed of the lapped sheets from the predetermined region along a different predetermined direction, stacking the sheets fed along the different predetermined direction, and increasing the reduced speed of feed of the lapped sheets prior to their reaching the predetermined region and substantially simultaneously decreasing the increased speed of feed of the lapped sheets beyond the predetermined region upon the commencement of the stacking of the sheets fed along the different predetermined direction.

22. A method of feeding and stacking sheets that comprises feeding the sheets in lapped relation to a predetermined region, feeding the lapped sheets thereafter beyond the predetermined region along a predetermined direction, stacking the sheets fed along the predetermined direction, clearing the predetermined region of sheets during the feeding of the sheets, thereupon transferring the feed of the lapped sheets from the predetermined region along a different predetermined direction, and stacking the sheets fed along the different predetermined direction.

23. A sheet-feeding machine having, in combination, means for feeding sheets in lapped relation to a predetermined region, means for feeding the sheets in lapped relation thereafter beyond the predetermined region along a predetermined direction, means for clearing the predetermined region of the lapped sheets during the feeding of the lapped sheets, and means for thereupon transferring the feed of the lapped sheets from the predetermined region along a different predetermined direction.

24. A sheet-feeding machine having, in combination, means for feeding sheets in lapped relation to a predetermined region, means for feeding the lapped sheets thereafter beyond the predetermined region along a predetermined direction at a predetermined speed, means for increasing the speed of feed of a plurality of the lapped sheets above the predetermined speed beyond the predetermined region in order to clear the predetermined region of the lapped sheets, and means for thereupon transferring the feed of the lapped sheets from the predetermined region along a different predetermined direction.

25. A sheet-feeding machine having, in combination, means for feeding sheets in lapped relation to a predetermined region, means for feeding the lapped sheets thereafter beyond the predetermined region along a predetermined direction at a predetermined speed, means for increasing the speed of feed of a plurality of the lapped sheets above the predetermined speed beyond the predetermined region in order to clear the predetermined region of the lapped sheets,

means for thereupon transferring the feed of the lapped sheets from the predetermined region along a different predetermined direction, and means for thereafter reducing the increased speed of feed beyond the predetermined region.

26. A sheet-feeding machine having, in combination, means for feeding sheets in lapped relation to a predetermined region at a predetermined speed, means for feeding the sheets in lapped relation thereafter beyond the predetermined region along a predetermined direction, means for reducing the speed of feed of a plurality of the lapped sheets below the predetermined speed prior to their reaching the predetermined region in order to clear the predetermined region of the lapped sheets, and means for thereupon transferring the feed of the lapped sheets from the predetermined region along a different predetermined direction.

27. A sheet-feeding machine having, in combination, means for feeding sheets in lapped relation to a predetermined region at a predetermined speed, means for feeding the sheets in lapped relation thereafter beyond the predetermined region along a predetermined direction, means for reducing the speed of feed of a plurality of the lapped sheets below the predetermined speed prior to their reaching the predetermined region in order to clear the predetermined region of the lapped sheets, means for thereupon transferring the feed of the lapped sheets from the predetermined region along a different predetermined direction, and means for thereafter increasing the reduced speed of the lapped sheets prior to their reaching the predetermined region.

28. A sheet-feeding machine having, in combination, means for feeding sheets in lapped relation to a predetermined region and thereafter beyond the predetermined region along a predetermined direction, means for reducing the speed of feed of a plurality of the lapped sheets prior to their reaching the predetermined region and for substantially simultaneously increasing the speed of feed of a plurality of the lapped sheets beyond the predetermined region in order to clear the predetermined region of the lapped sheets, means for thereupon transferring the feed of the lapped sheets from the predetermined region along a different predetermined direction, and means for thereafter substantially simultaneously increasing the reduced speed and reducing the increased speed of feed of the lapped sheets.

29. A sheet-feeding machine having, in combination, means for feeding sheets in a predetermined lapped relation to a predetermined region, means for feeding the sheets in lapped relation thereafter beyond the predetermined region along a predetermined direction, means for increasing the degree of lapping of a plurality of the lapped sheets prior to their reaching the predetermined region in order to clear the predetermined region of sheets, means for thereupon transferring the feed of the lapped sheets from the predetermined region along a different predetermined direction, and means for thereafter reducing the degree of lapping of the sheets to feed the sheets again in the predetermined lapped relation.

30. A sheet-feeding machine having, in combination, means for feeding sheets in lapped relation to a predetermined region and thereafter beyond the predetermined region along a predetermined direction, means for reducing by a predetermined factor the speed of feed of a plurality

of the lapped sheets prior to their reaching the predetermined region and for substantially simultaneously increasing by a greater factor the speed of feed of a plurality of the lapped sheets beyond the predetermined region in order to clear the predetermined region of the lapped sheets, means for thereupon transferring the feed of the lapped sheets from the predetermined region along a different predetermined direction, and means for thereafter substantially simultaneously increasing the reduced speed and reducing the increased speed of feed of the lapped sheets.

31. A sheet-feeding machine having, in combination, means for feeding sheets in lapped relation to a predetermined region, and thereafter beyond the predetermined region along a predetermined direction, a first stacking means for stacking the lapped sheets fed along the predetermined direction, means for reducing the speed of feed of a plurality of the lapped sheets prior to their reaching the predetermined region and for substantially simultaneously increasing the speed of feed of a plurality of the lapped sheets beyond the predetermined region in order to clear the predetermined region of the lapped sheets when the stack of sheets has attained a predetermined height, means for thereupon transferring the feed of the lapped sheets from the predetermined region along a different predetermined direction, a second stacking means for stacking the lapped sheets fed along the different predetermined direction, and means for thereafter substantially simultaneously increasing the reduced speed and reducing the increased speed of feed of the lapped sheets.

32. A sheet-feeding machine having, in combination, means for feeding sheets in lapped relation to a predetermined region and thereafter beyond the predetermined region along a predetermined direction, means for stacking the lapped sheets fed along the predetermined direction, a reject chute, means for reducing the speed of feed of a plurality of the lapped sheets prior to their reaching the predetermined region and for substantially simultaneously increasing the speed of feed of a plurality of the lapped sheets beyond the predetermined region in order to clear the predetermined region of the lapped sheets when it is desired to reject sheets, and means for thereupon transferring the feed of the lapped sheets from the predetermined region to the reject chute.

33. A sheet-feeding machine having, in combination, a switch, means for feeding sheets in lapped relation to and upon the switch, a plurality of means for respectively feeding the lapped sheets beyond the switch along any of a plurality of directions, means for reducing the speed of feed of a plurality of the lapped sheets to the switch prior to their reaching the switch and substantially simultaneously increasing the speed of feed of a plurality of the lapped sheets beyond the switch in order to clear the switch of the lapped sheets, means for thereupon actuating the switch to direct the lapped sheets from any of the plurality of feeding means toward any other of the plurality of feeding means while the switch is cleared of the lapped sheets, and means for thereafter substantially simultaneously increasing the said reduced speed of the lapped sheets to the switch and reducing the said increased speed of feed of the lapped sheets beyond the switch.

34. A sheet-feeding machine having, in combination, a switch, means for feeding sheets in

21

lapped relation to and upon the switch, a plurality of means for respectively feeding the lapped sheets beyond the switch along any of a plurality of directions, a plurality of stacking means, one corresponding to each of the plurality of feeding means, for stacking the lapped sheets fed along the corresponding feeding means, means for reducing the speed of feed of a plurality of the lapped sheets to the switch prior to their reaching the switch and substantially simultaneously increasing the speed of feed of a plurality of the lapped sheets beyond the switch in order to clear the switch of the lapped sheets, means for thereupon actuating the switch to direct the lapped sheets from any of the plurality of feeding means and the corresponding stacking means toward any other of the plurality of feeding means and the corresponding stacking means while the switch is cleared of the lapped sheets, and means for thereafter substantially simultaneously increasing the said reduced speed of the lapped sheets to the switch and reducing the said increased speed of feed of the lapped sheets beyond the switch.

35. A sheet-feeding machine having, in combination, a switch, means for feeding sheets in lapped relation to and upon the switch, means for respectively feeding the lapped sheets beyond the switch along any of a plurality of directions, stacking means for receiving and stacking the lapped sheets fed along one of the plurality of directions, a reject chute disposed along another of the plurality of directions for receiving the lapped sheets fed therewith, means for reducing the speed of feed of a plurality of the lapped sheets to the switch prior to their reaching the switch and substantially simultaneously increasing the speed of feed of a plurality of the lapped sheets beyond the switch in order to clear the switch of the lapped sheets, means for thereupon actuating the switch to direct the lapped sheets from one of the plurality of directions toward any other of the plurality of directions while the switch is cleared of the lapped sheets, and means for thereafter substantially simultaneously increasing the said reduced speed of the lapped sheets to the switch and reducing the said increased speed of feed of the lapped sheets beyond the switch.

36. A sheet-feeding machine having, in combination, a first conveyor, a first motor normally connected to the first conveyor to actuate the first conveyor in order to feed sheets in lapped relation to a predetermined region, a second conveyor, a second motor normally connected to the second conveyor to actuate the second conveyor in order to feed the lapped sheets thereafter beyond the predetermined region along a predetermined direction, a third motor for actuating the first conveyor at reduced speed, a fourth motor for actuating the second conveyor at increased speed, means for simultaneously disconnecting the first and second motors from the respective first and second conveyors and for connecting the third and fourth motors to the respective first and second conveyors in order to reduce the speed of feed of the lapped sheets by the first conveyor to the predetermined region and to increase the speed of feed of the lapped sheets by the second conveyor beyond the predetermined region, thereby to clear the predetermined region of the lapped sheets, means for thereupon transferring the feed of the lapped sheets from the predetermined region along a different predetermined direction, and means for thereafter simultane-

22

ously disconnecting the third and fourth motors from the respective first and second conveyors and for reconnecting the first and second motors to the respective first and second conveyors in order to increase the reduced speed of feed of the lapped sheets by the first conveyor to the predetermined region and to reduce the increased speed of feed of the lapped sheets by the second conveyor beyond the predetermined region.

- 10 37. A sheet-feeding machine having, in combination, a first conveyor, a first motor for actuating the first conveyor, a first electric circuit for operating the first motor, a first switch for opening and closing the first electric circuit, a second conveyor, a second motor for actuating the second conveyor, a second electric circuit for operating the second motor, a second switch for opening and closing the second electric circuit, a third motor for actuating the first conveyor at reduced speed, a third electric circuit for operating the third motor, a third switch for opening and closing the third electric circuit, a fourth motor for actuating the second conveyor at increased speed, a fourth electric circuit for operating the fourth motor, a fourth switch for opening and closing the fourth electric circuit, means for simultaneously actuating the third and fourth switches to open the circuits of the third and fourth motors and the first and second switches to close the circuits of the first and second motors to connect the first motor to the first conveyor and the second motor to the second conveyor to actuate the first conveyor in order to feed sheets in lapped relation to a predetermined region and to actuate the second conveyor in order to feed the lapped sheets thereafter beyond the predetermined region along a predetermined direction and for simultaneously actuating the first and second switches to open the circuits of the first and second motors and the third and fourth switches to close the circuits of the third and fourth motors to disconnect the first and second motors from the respective first and second conveyors and to connect the third and fourth motors to the respective first and second conveyors in order to reduce the speed of feed of the lapped sheets by the first conveyor to the predetermined region and to increase the speed of feed of the lapped sheets by the second conveyor beyond the predetermined region, thereby to clear the predetermined region of the lapped sheets, and means for thereupon transferring the feed of the lapped sheets from the predetermined region along a different predetermined direction.
- 15 38. A sheet-feeding machine having, in combination, a switch that may be oriented along any of a plurality of predetermined directions in order that it may direct sheets that may be fed to and upon the switch along the corresponding direction, means for feeding sheets to and upon the switch at a time when it is oriented along one of the said predetermined directions, means for feeding the sheets thereafter beyond the switch along the predetermined direction, means for increasing the speed of feed of a plurality of the sheets beyond the switch in order to clear the switch of sheets, and means for thereupon orienting the switch along any of the other predetermined directions while cleared of sheets.
- 20 39. A sheet-feeding machine having, in combination, a switch that may be oriented along any of a plurality of predetermined directions in order that it may direct sheets that may be fed to and upon the switch along the corresponding direction, means for feeding sheets to and upon

the switch at a time when it is oriented along one of the said predetermined directions, means for feeding the sheets thereafter beyond the switch along the predetermined direction, means for reducing the speed of feed of a plurality of the sheets prior to their reaching the switch in order to clear the switch of sheets, and means for thereupon orienting the switch along any of the other predetermined directions while cleared of sheets.

40. A sheet-feeding machine having, in combination, a switch that may be oriented along any of a plurality of predetermined directions in order that it may direct sheets that may be fed to and upon the switch along the corresponding direction, means for feeding sheets to and upon the switch at a time when it is oriented along one of the said predetermined directions, means for feeding the sheets thereafter beyond the switch along the predetermined direction, means for reducing the speed of feed of a plurality of the sheets prior to their reaching the switch in order to clear the switch of sheets, means for thereupon orienting the switch along any of the other predetermined directions while cleared of sheets, and means for thereafter increasing the reduced speed of the sheets prior to their reaching the switch.

41. A sheet-feeding machine having, in combination, a switch that may be oriented along any of a plurality of predetermined directions in order that it may direct sheets that may be fed to and upon the switch along the corresponding direction, means for feeding sheets to and upon the switch at a time when it is oriented along one of the said predetermined directions and thereafter beyond the switch along the predetermined direction, means for reducing the speed of feed of a plurality of the sheets prior to their reaching the switch and for substantially simultaneously increasing the speed of feed of a plurality of the sheets beyond the switch in order to clear the switch of sheets, means for thereupon orienting the switch along any of the other predetermined directions while cleared of sheets, and means for thereafter substantially simultaneous-

ly increasing the reduced speed and reducing the increased speed of feed of the sheets.

42. A sheet-feeding machine having, in combination, conveying means for feeding sheets to a predetermined region, means for feeding the sheets thereafter beyond the predetermined region along a predetermined direction, means for reducing the speed of the conveying means to reduce the speed of feed of the sheets prior to their reaching the predetermined region in order to clear the predetermined region of sheets, means for thereupon transferring the feed of the sheets from the predetermined region along a different predetermined direction, and means for thereafter increasing the reduced speed of the sheets prior to their reaching the predetermined region.

43. A sheet-feeding machine having, in combination, conveying means for feeding sheets to a predetermined region at a first predetermined speed, means for feeding the sheets thereafter beyond the predetermined region at a second predetermined speed along a predetermined direction, means for reducing the speed of the conveying means to reduce the speed of feed of the sheets below the first predetermined speed prior to their reaching the predetermined region and for increasing the speed of feed of a plurality of the sheets above the second predetermined speed beyond the predetermined region in order to clear the predetermined region of sheets, and means for thereupon transferring the feed of the sheets from the predetermined region along a different predetermined direction.
